(57) **CLAIM**

The ornamental design for a motorcycle-themed rocking device, as shown and described.

DESCRIPTION

FIG. 1 is a front perspective view of a rocking device showing a new ornamental design for a rocking device; FIG. 2 is a front view thereof, the back view being a mirror image;

FIG. 3 is a left side view thereof, the right side view being a mirror image;

FIG. 4 is a top view thereof;

FIG. 5 is a front perspective view of a second embodiment of my design;

FIG. 6 is a front view of FIG. 5;

FIG. 7 is a left side view of FIG. 5, the right side view being a mirror image; and,

FIG. 8 is a top view of FIG. 5.
